(57) **CLAIM**

The ornamental design for a notebook computer as shown and described.

DESCRIPTION

FIG. 1 is a perspective view of a notebook computer showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged view of the portion, labeled '8' of FIG. 1;

FIG. 9 is a cross-sectional perspective view taken along line 9-9 in FIG. 2;

FIG. 10 is a cross-sectional perspective view taken along line 10-10 in FIG. 2;

FIG. 11 is an enlarged view of the portion, labeled '11' of FIG. 9;

FIG. 12 is an enlarged view of the portion, labeled '12' of FIG. 10;

FIG. 13 is a perspective view thereof in an alternate state of use; and,

FIG. 14 is a perspective view thereof in another alternate state.

The evenly-dashed broken lines illustrate portions of the notebook computer that form no part of the claimed design. The long dash-short dash broken line defines the boundary of the claim design, which extends to the boundary but does
